Patented Sept. 22, 1914.

UNITED STATES PATENT OFFICE.

CHARLES M. TERRY, OF GARY, INDIANA.

SCALE-REMOVER.

1,111,330.

Specification of Letters Patent. Patented Sept. 22, 1914.

Application filed October 24, 1913. Serial No. 797,010.

To all whom it may concern:

Be it known that I, CHARLES M. TERRY, a citizen of the United States of America, and resident of Gary, county of Lake, and State of Indiana, have invented certain new and useful Improvements in Scale-Removers, of which the following is a specification.

This invention relates to improvements in scale removers for rolling mills.

10 A further object is a scale remover which has few operating parts and which may readily be attached to any rolling mill now in use.

These and other objects are attained in the 15 apparatus described in the following specification and illustrated in the accompanying drawings, in which,

Figure 1 is a perspective view of a rolling mill showing the scale removers in position. Fig. 2 is a transverse sectional view taken on line 2—2 of Fig. 1. Fig. 3 is a fragmental perspective view of the grinding bar.

The apparatus consists of a rotatably 25 mounted grinding bar 4 and an operating mechanism 5, for bringing the grinding bar into contact with one of the rolls. A similar grinding bar 4 and operating mechanism 5 is provided for the other roll 6.

30 The grinding bar 4 extends the entire length of the roll and comprises a metal bar 7, having an undercut slot 8 formed in one face thereof, and a carborundum strip 9, on which a key 10 is formed. The key engages the undercut slot 8, as shown in Fig. 3. The grinding bars are provided with journal lugs 11, which are suitably journaled in the rolling mill housing 12, adjacent to the rolls 6, as shown in Fig. 2, so 40 that the carborundum strips 9 may engage the surface of the rolls, when the bars are rotated as indicated in Fig. 2.

The means for operating the upper grinding bar comprises a ratchet 13, rigidly secured to the projecting end of one of the journals 11, a lever 14, rotatably mounted on the end of the journal 11, adjacent to the ratchet, an operating pawl 15, pivotally mounted on the lever to engage the ratchet 50 teeth, and a locking pawl 16, pivotally mounted on the housing 12, to likewise engage the ratchet teeth.

The lower operating lever 14' is rotatably mounted on a pin 17, fixed in the housing 12, 55 with the ratchet wheel 13' located between the pin 17 and the handle 18 of the lever.

An operating pawl 15' is located on the lever 14', between the pivot pin 17 and the ratchet wheel 13', and engages the ratchet teeth, while a locking pawl 16' is pivoted on 60 the housing and engages the teeth of the ratchet 13'.

The different relative positions of the lever pivots 11 and 17, and of the pawls 15, 15', 16, 16', are for the purpose of giving the 65 grinding bars opposite rotative movements, as indicated by the arrows in Fig. 2, in response to a downward pressure on either of the levers 14 or 14'.

The teeth of the ratchets 13 and 13' are 70 reversed with relation to one another, in order to accomplish this change in movements.

In operation: When the rolling mill attendant observes the slightest formation of 75 scale on the surfaces of the rolls, he bears downwardly upon the levers 14 and 14', and in so doing rotates the grinding bars in a direction opposed to the direction of rotation of the rolls, thus bringing the carborundum strips 9 into engagement with the roll surfaces. In forcing the levers down, the locking pawls 16 and 16' drop into locking 80 engagement with the teeth of the ratchets 13 and 13' and hold the grinding 85 bars in engagement with the rolls. When the scale has been removed, the grinding bars are moved away from the roll surfaces, by releasing the locking pawls 16 and 16', by means of the handles 16^a and 16^b. The 90 above described operation of removing scale is carried on from time to time, as soon as the operator observes any scale formation, and it is accomplished without stopping the use of the machine, and the mechanism is 95 operated by the operator of the mill without another's assistance.

Having thus described my invention, what I claim is:

1. A scale removing device for mill rolls 100 consisting of a bar with eccentric journals mounted in bearings adjacent to the periphery of the roll, and means for rotating the bar to carry it into and out of contact with the roll, said means being located externally to the ends of the rolls, whereby the bar may be actuated while the rolls are in operation.

2. A scale removing device for mill rolls 110 comprising a rolling mill housing, mill rolls journalled in the housing, a bar mounted adjacent to the periphery of a roll and hav-

ing journals projecting upon the exterior of the housing, and means mounted upon the journals external to the housing and adapted to rotate the bar to bring it into contact with the surface of the roll.

3. In combination in a grinding device for rolls, a pivotally mounted grinding bar, a pivotally mounted operating lever located adjacent to the grinding bar, and means for 10 intermittently connecting the lever with the grinding bar.

4. A roll grinding device comprising a housing, a roll journaled in the housing, a grinding bar pivoted in the roll housings 15 adjacent to the roll, and means for causing the grinding bar to engage the roll, said means comprising a ratchet, a lever mounted

adjacent to the ratchet, and a pawl mounted on the lever and engaging the ratchet.

5. A scale remover for rolling mills comprising a mill housing, a grinding bar pivotally mounted in the mill housing, a ratchet fixed to the grinding bar, a lever pivotally mounted adjacent to the ratchet, a pawl mounted on the lever and engaging the 20 ratchet, and a second pawl mounted on the housing and engaging the ratchet. 25

In testimony whereof, I have hereunto subscribed my name this 30th day of August, 1913.

CHARLES M. TERRY.
